UNITED STATES PATENT OFFICE.

RUDOLPH F. HAMAKER AND WILLIAM H. VIRGIN, OF NEW ORLEANS, LOUISIANA.

INTERCHANGEABLE AIR-BRUSH.

1,333,488.

Specification of Letters Patent. Patented Mar. 9, 1920.

Application filed November 12, 1918. Serial No. 262,157.

To all whom it may concern:

Be it known that we, RUDOLPH F. HAMAKER and WILLIAM H. VIRGIN, citizens of the United States, residing at New Orleans, 5 in the parish of Orleans and State of Louisiana, have invented certain new and useful Improvements in Interchangeable Air-Brushes, of which the following is a specification.

10 This invention comprehends generally improvements in that class of inventions known as coating and more particularly has reference to an interchangeable air brush.

It is the primary aim and object of the 15 present invention to provide a device designed for spraying liquid colors, dry metallic powders, etc., and embodies generally a holder in which may be detachably fitted either a liquid spraying nozzle or a 20 powder spraying nozzle, while mounted in the handle and communicating with a supply of air under pressure, is manually operable valve means for controlling the passage of air to the handle and the nozzle for 25 the effective spraying of the material by the nozzle which is fitted in the holder or handle.

It is an additional object of this invention 30 to provide a device of the above mentioned character wherein the powder spraying nozzle is of novel construction and is designed with a detachable connection between the nozzle body and the powder holder so that a holder containing any desired color 35 may be connected to the nozzle body.

The invention also embraces the provision 40 of a device of the above mentioned character wherein the spraying nozzles are provided with main valve means for controlling the spraying action, and this valve means is primarily designed to regulate the flow of the color or powder.

It is a more specific object of the present 45 invention to provide the powder spraying nozzle with an auxiliary air passage designed to removably receive a valve controlled auxiliary nozzle which is also arranged in the color holder so as to assist in the movement of the color toward the outlet 50 of the main nozzle and at the same time serves to lock the holder against displacement.

Among the other aims and objects of this 55 invention may be recited the provision of a device of the above mentioned character wherein the number of parts are few, the

construction simple, the cost of production low, and the efficiency high.

The improvements in the details and arrangement of parts will be apparent from 60 an inspection of the accompanying drawings, in connection with the specific description hereinafter contained, and wherein the preferred embodiment of the invention is disclosed for the purpose of imparting a full 65 understanding of the invention.

The invention is clearly illustrated in the accompanying drawings, in which:

Figure 1 is a longitudinal sectional view 70 of the improved device with the detachable powder spraying tip or nozzle shown mounted in the holder,

Fig. 2 is a top plan view thereof, and

Fig. 3 is a vertical longitudinal sectional detail of a detachable liquid spraying tip 75 or nozzle.

Similar characters of reference are employed in all of the above described views, to indicate corresponding parts.

Referring now, more particularly, to the 80 accompanying drawings, there is provided a handle 1 preferably having a tubular body one end of which is closed while the other end is open and adapted to receive either a powder containing tip generally designated 85 2 or the liquid spraying tip generally designated 3. Coöperating with these tips is the improved valve means indicated in its entirety by the numeral 4, designed primarily for controlling the passage of compressed air to and through the handle and 90 through the tip connected to the handle. The valve means, preferably consists of a casing composed of spaced sections 5 and 6 mounted in opposed relation in the handle 95 and preferably formed integral therewith. The section 5 is formed at its inner end with an opening about which is provided a valve seat 7, while a transverse bridge 8 is formed at the outer end of the section 5. A valve 100 stem 9 is slidably mounted through both of the sections through the bridge and carries a head 10 which is positioned in the section 5 for coacting with the seat 7 while also disposed about the stem is a coiled expansion 105 spring 11, positioned in the section 5 and having its respective ends bearing against the valve head 10 and the bridge 8. A knob 12 is connected to the outer projecting end of the stem to facilitate depression of the 110 stem against the tension of the spring for opening the valve to allow compressed air

to pass through the section 5 from a supply tube 13, which is connected to the section 5, and enter the handle and then pass through and out of the tip or nozzle which is connected to the handle. Packing material 14' may be mounted in the section 6 and held in position by a packing gland 15 to prevent the escape of the air.

- The improved detachable tip or nozzle 10 for spraying dry or powdered colors in the present instance may be said to consist of a body 14 of a conical configuration forming a main spraying nozzle, the inner portion of which is detachably engaged with the 15 outer end of the handle preferably through the instrumentality of threads 15, while interiorly the body is formed with a transversely extending and longitudinally inclined partition 16 terminates near the outer 20 open end and divides the body into a lower air chamber 17 and an upper color chamber 18. The inner end wall 19 of the body is formed with a central aperture 20, projecting inwardly therefrom is a spout or 25 nozzle 21, which directs the air from the handle toward the outlet opening in the body or main nozzle 14. A holder generally designated 22 is now employed and is designed to contain the dry or powdered colors 30 and constructed so as to detachably engage the body and communicates with the chamber 18. This holder preferably consists of a body from the lower end of which issues a threaded neck 23 for detachably engaging the threaded collar 24, which in turn is formed about an opening in the body 14 and communicating with the chamber 18. The inner surface of the neck is restricted and arranged in a conical form as at 25 to facilitate feeding of the powder to the chamber 18 while a filler cap 26 is detachably mounted on the top of the body of the holder 22. It is of course apparent that several of these holders 22 may be used in conjunction with one body 14, for containing various colors of powder, as is apparent. 40 To assist in the feeding of the powder toward the main outlet 27 in the body 14, a tube 28 is formed integral with the body 45 being led from the tube or secondary nozzle 21 as shown at 29 and projects through and above the inner portion of the body 14 while the upper projecting portion is preferably curved to conform to the curvature of the holder 22. This tube is formed near its 50 upper end with opposed openings 30 which are designed to register with another opening 31 in the holder 22 while fitted in these openings and projecting into the holder 22 is a spout or secondary nozzle 32, preferably of conical form and having openings therein for communicating with the tube so that air may pass from the tube into the holder and act against the powder therein. A manually 60 adjustable needle valve 33 is mounted in the 65

spout 32 to regulate the passage of air. In addition, it is to be apparent, that the spout serves as a means for locking the holder 22 against accidental turning movement, thereby insuring of an effective rigid connection 70 between the component parts forming the tip or nozzle 2.

With a view toward providing the main valve means for controlling the spraying action and regulating the amount of powder 75 used, a tubular casing 34 projects from the body 14 being preferably integral therewith and positioned opposite to the valve seat 35 provided at the outlet 27. Adjustably mounted in this casing is the stem 36 of a 80 needle valve 37 arranged to coact with the seat 35 and this stem is adjustable desirably through the instrumentality of a knob 38 carried at the outer projecting end thereof.

The improved detachable tip or nozzle 85 3 for spraying liquid colors in its preferred embodiment, may be said to consist of a body 37 of a conical configuration, the inner end of which is adapted for detachable engagement with the handle 1 by means of 90 threads 40, while the said inner end is partly closed by means of a partition 41, and the body is also provided with a transversely arranged and longitudinally upwardly inclined partition 42, the inner end of which 95 is joined with the lower edge of the end walls 40 and the inner walls of the body providing in effect a spout or nozzle 43 through which air under pressure passes. The outer end of the partition 42 of course, 100 terminates in an opening 44 which is positioned beneath another opening 45, forming a valve seat, and also provided by the partition 42. In addition, this partition forms a color chamber 46 with which is 105 detachably connected the liquid color holder 47. This holder is in the form of a cup-like body having a neck 48 issuing from the bottom thereof and threaded for removable engagement with the upstanding threaded collar 49, the latter communicating with the color chamber while a filler cap 50 serves to removably close the holder 47 being detachably engaged with the upper edge 110 thereof.

The main valve means for controlling the flow of liquid from the chamber 46 through the openings 45, desirably consists of a tubular casing 51 integral with and projecting above the body 39 and disposed in alignment 115 with the valve seat provided by the opening 45. A needle valve stem 52 is adjustably mounted as at 53 in the casing so that the point 54 will coact with the seat while a knob 55 is carried by the outer end of the 120 stem to regulate the adjustment thereof. In using this form of tip or nozzle, the valve is adjusted so that to regulate the flow through the openings, while the air under pressure 125 which passes through the secondary spout 130

43 which terminates in the opening 44, beneath the opening 45 will insure of the projecting of the liquid in a spray upon a surface.

- 5 In using the arrangement shown in Figs. 1 and 2, when the valve 10 is open, air under pressure passes into the handle through the spout 21 into the air chamber 17 in the tip and as this air passes from the tip it sprays 10 the powder, the flow or passage of which is regulated through the outlet 35 by the manually adjustable needle valve 37. During this action, air under pressure will also pass through the tube 28, thence through the 15 valve controlled spout 29' into the holder 22 to consequently assist in the movement of the powder toward the outlet 37.

It is believed in view of the foregoing description that a further detailed description 20 of the operation of the invention is entirely unnecessary. Likewise, it is believed that the advantages of the invention will be readily apparent.

Still further embodiments of the invention than those herein especially defined may be resorted to as conditions or preference may dictate, as may be in keeping with the hereto appended claims.

Having thus fully described our invention, what is claimed as new and desired to be secured by Letters Patent, is:

1. In a device of the character described, a conical shaped body adapted for detachable engagement with an air supplying member, having an apertured inner end wall and a partition dividing the body into a lower air chamber and an upper color receiving chamber, a secondary spout leading from the apertured end wall and projecting into 35 the body for directing compressed air to the air chamber toward the outlet end of the body, a color holder detachably connected to the body and communicating with the color receiving chamber, manually operable valve 40 means mounted in the body for regulating the passage of color from the body and for controlling the spraying action of the nozzle, an air conducting tube leading from the secondary nozzle and projecting through and above the body and formed with opposed 50 openings near the outer end, the color holder having an opening therein adapted to be registered with the openings in the tube and a valve controlled spout fitted through the 55 openings projecting into the holder and communicating with the tube so that the air passing therethrough will facilitate the feeding of the color and said spout incidentally serving as a lock for preventing accidental disengagement of the holder from the body. 60

2. In a device of the character described, in combination, a hollow handle, a spraying nozzle detachably fitted in and communicating with the handle, a color holder in connection with the nozzle, valve means for regulating passage of color through the nozzle, a valve casing carried by and communicating with the handle, a manually operable valve in the casing for controlling the passage of air into the handle and the nozzle, 70 and a conduit leading from the nozzle to the color holder.

3. In a device of the character described, in combination, a hollow handle, a spraying nozzle detachably fitted in and communicating with a handle, a color holder in connection with the nozzle, valve means for regulating passage of color through the nozzle, 75 a valve casing carried by and communicating with the handle, a manually operable valve in the casing for controlling the passage of air into the handle and the nozzle, a conduit leading from the nozzle to the color holder, and a valve arranged in said conduit 80 for controlling communication between the latter and the color holder.

In testimony whereof we affix our signatures hereto.

RUDOLPH F. HAMAKER.
WILLIAM H. VIRGIN.
